United States Patent Office.

CHARLES KIRCHHOF, OF NEWARK, NEW JERSEY.

Letters Patent No. 72,506, dated December 24, 1867.

IMPROVEMENT IN CANDLE-HOLDERS.

The Schedule referred to in these Letters Patent and making part of the same.

TO ALL WHOM IT MAY CONCERN:

Be it known that I, CHARLES KIRCHHOF, of Newark, county of Essex, State of New Jersey, have invented a new and improved Candle-Holder; and I do hereby declare that the following is a full and exact description thereof, reference being had to the accompanying drawing, and to the letters of reference marked thereon.

The nature of my invention consists in the construction of an arrangement for conveniently attaching candles, ornaments, or other objects to and maintaining above any oscillating support, (as the branches of a tree,) in their proper position.

I will now proceed to describe my construction and operation.

The construction of my device is based upon the principle of a double-armed pendulum. The weight attached to the short arm, above the support of suspension, is counterbalanced by means of an over-weight fastened on a longer arm suspending, and commands, by its gravity, the perpendicular position of the combination.

A hook, as shown in Figure, *a b*, extending towards *c* and *d*, and made of the required material, may be so arranged as to be conveniently attached, either by the curved part *a*, or the point *b*, to the support *s s*, and easily removed again. The short part *c*, extending upwards, may be supplied with a candlestick, *e*, or any other object desired, the several-times larger part, *d*, by means of a ball, *f*, fruit, or any other object of sufficient gravity, attached to its end, being all that is required for the successful operation. It is obvious that the whole combination may consist of one or more pieces of a variety of materials, if arranged according to my principle.

Having described my invention, I will now state what I desire to secure by Letters Patent, viz:

I claim, as a new article of manufacture, the hook *a b*, in combination with rod *d*, ball *f*, and holder *c*, or any equivalent, when constructed and arranged in the manner described, and for the purpose specified.

CHARLES KIRCHHOF.
